UNITED STATES PATENT OFFICE.

WILLIAM H. McNUTT, OF NEW YORK, N. Y., ASSIGNOR TO CARRIE EMMA OWEN, OF FRANKLIN, NEW YORK.

VALVED FUSIBLE PLUG.

1,187,636.

Specification of Letters Patent. Patented June 20, 1916.

Application filed September 17, 1913. Serial No. 790,221.

To all whom it may concern:

Be it known that I, WILLIAM H. McNUTT, a citizen of the United States, and resident of New York city, in the county of New York and State of New York, have invented certain new and useful Improvements in Valved Fusible Plugs, of which the following is a specification.

This invention relates to a safety device 10 in the form of a valved fusible plug, in which the main portion or body of the device is formed of a readily fusible material or alloy, and is adapted to screw into a suitable threaded opening or sput in a receptacle, and which has its bore provided 15 with a valve that is normally closed and can open from abnormal internal pressure in the container.

The object of this invention is to provide 20 means to permit the immediate escape or release of explosive gas or vapor generated in the receptacle, and upon a fire occurring in the vicinity, the entire body member of the device will very quickly soften and be 25 blown out of the receptacle, thus providing free escape for the gas or vapor.

In the accompanying drawing illustrating 30 embodiments of my invention, Figure 1 is a vertical section of the device; Fig. 2 is a plan view; Fig. 3 is an elevation; Fig. 4 shows the plug applied to a plumber's torch; Fig. 5 shows the plug combined with a bushing; Fig. 6 is a plan of the device as shown 35 in Fig. 5; and Fig. 7 is a bottom view of the same.

The valved fusible plug is shown as comprising a body denoted generally by 6, provided with a valve 7 in its bore that is held normally closed by a spring 8.

The body 6 is formed tubular, being externally screw-threaded at 9, and provided with a wrench-engaging head 10, which is hexagonal in contour; and the said body is made of a readily fusible material or alloy, that will soften or melt at a comparatively 45 low temperature, such as about 400° F.

The bore 12 of the body serves to guide the stem 13 of the valve 7, that is freely slideable in the bore, so as to permit outflow of 50 the gas or vapor from the receptacle. At the outer end the bore may be enlarged or countersunk, to form a recessed valve seat at 14, for the valve 7, so that the valve will

be protected from injury or displacement by being positioned below the outer or top 55 wall of the head.

The stem 13 of the valve is shown projecting down below or beyond the body 6, and is surrounded by a coil spring 8, which is compressed between the lower end of the 60 body and the lower end portion of the stem, to thereby retain the valve seated by spring pressure.

The stem 13 is shown as threaded to carry a nut 15, which engages one end of the 65 spring 8; and as the other end of the spring is confined by the end of the body, by turning this nut on the stem (or vice versa), the tension of the spring will be adjusted.

The coil spring 8 is shown as having one 70 end projecting into the body 6, and preferably secured therein; and the other end of the spring is inserted into a hole in the nut 15, and fastened therein, whereby the nut is prevented from turning relative to the body. 75

The valve 7 is shown as being provided with a tool-engaging portion at the top, such as a slot 17; and by turning the valve with a screw-driver, since the nut is prevented from rotating relative to the head, 80 the nut must travel toward, or away from the body, and thus the tension of the spring can be adjusted from the outside of the receptacle, and after the valved plug has been 85 secured in the receptacle.

I have discovered by experiment that the body member 6 can be made by the process known as "die-casting" and of a readily fusible alloy or composition. With this process, the body member and its threaded portion and countersunk bore, are properly shaped, and the member is in finished condition when removed from the dies; without any machining whatever, or any mechanical manipulation at all being necessary. 95

In Fig. 4 the valved fusible plug is shown 100 screwed into a threaded sput 18, in the top of a plumber's torch 19.

In the use of the device, any abnormal 105 pressure in the receptacle will serve to raise the valve permitting the immediate escape of the gas or vapor. On the occurrence of a fire in the vicinity, the heat therefrom, or that of the ignited gas or vapor escaping 105 through the bore around the valve, will

- cause the body to melt or soften, and the body will then be blown out of the receptacle, providing a relatively large opening for the escape of the confined gas or vapor.
- 5 With the use of the valve fusible plug or large receptacles, it is desirable to employ protecting means against back-fire of burning gas or vapor into the receptacle, such as a shield of perforated sheet metal.
- 10 In Fig. 5 is shown a flame-proof bushing 20, that is externally screw-threaded at 21, to screw into a sput 22, and whose lower end is closed by a disk 23 of thin sheet metal having minute flame-proof apertures.
- 15 The bore 24 of the bushing is somewhat larger than the head 10 of the body of the fusible plug, to permit the body to be screwed into the reduced threaded portion 25 of the bushing. With the use of such a structure, when heat is evolved sufficient to soften the body of the plug, it will be blown out of the bushing, and the perforated disk
- 20

23 will prevent flame passing down into the receptacle.

Having thus described my invention, what I claim is:—

A valved fusible plug, comprising a tubular body composed entirely of readily fusible material that is externally screw-threaded and provided with a wrench-engaging head at one end, the bore of the body being enlarged at the head end, a valve seated in the latter portion of the bore with its stem freely slideable in the bore and projecting beyond the body, and a coil spring 30 on the valve stem compressed between the end of the body and the end of the stem to hold the valve seated to open from internal pressure.

WILLIAM H. McNUTT.
